DESIGN FOR A SILO LUG

Peter Rutten, Plainfield, Ill.

Application September 22, 1938, Serial No. 80,036

Term of patent 14 years

To all whom it may concern:

Be it known that I, Peter Rutten, a citizen of the United States and residing in the village of Plainfield, county of Will and State of Illinois, have invented a new, original, and ornamental Design for a Silo Lug, of which the following is a specification, reference being had to the accompanying drawing, forming a part thereof, wherein,

Fig. 1 is a perspective view illustrating a silo lug showing my new design;

Fig. 2 is a plan view of the silo lug;
Fig. 3 is a side elevation of the same, and
Fig. 4 is an end elevation of the silo lug, Figs.
2, 3 and 4 being shown on an enlarged scale.

I claim:

The ornamental design for a silo lug, substantially as shown.

PETER RUTTEN.
